FUNNEL-LIKE CAP FOR URINE SPECIMEN BOTTLES

Orie J. Bachechi, Albuquerque, N. Mex.

Application August 19, 1955, Serial No. 37,582

Term of patent 14 years

(Cl. D83—1)

Fig. 1

Fig. 2

Fig. 1 is a side elevational view of a funnel-like cap for urine specimen bottles showing my new design;

Fig. 2 is a left end elevation of the funnel-like cap shown in Fig. 1; and

Fig. 3 is a top plan view of the funnel-like cap of Figs. 1 and 2.

I claim:

The ornamental design for a funnel-like cap for urine specimen bottles, as shown.
